UNITED STATES PATENT OFFICE

EDWARD F-G. GIBBS, OF DETROIT, MICHIGAN

METHOD OF FORMING TURNING TOOL HOLDERS

Continuation of application Serial No. 602,987, filed November 24, 1922. This application filed December 21, 1927. Serial No. 241,620.

This invention relates to new and useful improvements in what is known as a "turning tool holder", which is held in the tool post of the common engine lathe and other machine tools and which, in turn, holds the inserted cutter-bit or cutting tool. The device manufactured in accordance with this invention is used chiefly in turning, facing and planing of metals. I do not mean to limit myself, however, in any sense, except as required by the scope of the claims.

The objects sought in this invention are to produce a one-piece holder of maximum strength; the construction of which will suggest "short hold", to the unthinking operator; which will enable the use of inserted cutters of indefinite lengths; give them the proper angle or inclination; facilitate the production of a good cutter-seat and facilitate economy and protection in its manufacture.

I attain these objects by the construction hereinafter described, illustrated in the accompanying drawings, which form a part 25 of this specification, and then specifically defined in the appended claims.

Referring now to the said drawings by figures:—

Figure 1 is a side elevation of the tool holder complete, with the cutting tool in working position.

Figure 2 is a plan view of the tool holder alone.

Figure 3 is a sectional view of the finished holder, (for square cutters) from the rear, on the line 3, 3, of Figure 1.

Figure 4 is a sectional view of the same, on line 4, 4, of Figure 1.

Figure 5 is a sectional view of the same, 40 on line 5, 5, of Figure 1.

Figure 6 is a rear end outline of the unfinished holder.

Figure 7 is a sectional view of the finished holder, (for rectangular cutters) from the 45 rear, on line 3, 3, of Figure 1, and

Figure 8 is a bottom view of the holder alone.

Reference now being had to the drawing by letter, in which similar letters refer to 50 similar parts throughout the several views,

a designates the one-piece holder proper; *b* the flat section of the horizontal bearing surface for the tool post screw; *c* the convex section of same; *d* designates first the major channel hole or bore and later the elongated rear section of the internal cutter-holding channel; *e* the neat fitting rectangular constricted front section of the same; *f* the cutter bit or cutting tool; *g* the rib or bulge on each side of the original forging, which afterwards is pressed in, or down; *h* the cutter clamping set screw; *i* the two slight depression lines on each side of the holder; and *j* the flat bottom bearing surface of the holder.

It is to be seen from Figs. 1, 2 and 4, that the central section *b* of the holder's top surface, on which the tool post screw bears is horizontal and flat, while the rear section *c*, of the same is convex. It is also seen from Figs. 1 and 6 that section *b* is higher than section *c*. The reason for thus differentiating the forms of the said two sections, and placing the preferable one in front, is to remind and induce the unthinking operator to set the holder as far back in the tool post as possible, in order to make it as rigid as possible.

It is also to be seen that the internal cutter-channel, *d* and *e*, which carries the rectangular cutter to which it is adapted, is tubular and runs the entire length of the straight one-piece holder; both terminals of which are wholly within the respective ends of the said holder; leaving its flat bottom bearing surface an unbroken plane.

This centrally disposed channel weakens the holder least, enables the use of cutters of indefinite lengths, and reduces the inclination of the cutting tool to about five degrees, the proper angle.

The advantageous features mentioned in the foregoing sentence, as well as economy in manufacture and good cutting tool seats are made practical by the peculiar steel forging's shape and manner of which and in which this holder is made. The said forging comes with a temporary rib or bulge *g*, on both sides from the rear end up to its head. The major hole *d* is first drilled from the said rear end, concentrically between the said ribs 100

up to the said head; or about three-fourths its entire length. The hole or bore thus obtained is just about large enough for the proposed cutting tool, if square, to slip in with very little, if any, broaching, but the 5 side walls are thus partially cut away. The bore is extended by running a smaller or constricted bore *e* through the head, or about one-fourth of the entire length. When this 10 constricted bore is broached out to neatly engage the rectangular cutter, the forging is heated, the said ribs pressed down flat or in, by external pressure, which restores the side walls, and then a finishing broach is run 15 through and through. This pressing down operation or flattening of the ribs is for the purpose of making the distance between the side walls of the major or large bore equal to the diameter of the reduced continuation 20 or smaller bore. Thus we get a long tubular cutter-holding channel, a good broached hole or bore, and a good cutter-seat under the set screw *h*, the major bore elongated in the cross section, leaving straight vertical side walls, 25 and we eliminate about three-fourths of the expensive broaching.

Furthermore the cutters now used are square but the rectangular cutter, proportioned $1\frac{1}{2}$ to 1, is preferred to the simple 30 square one, but the cost of elongating the channel therefor, by broaching is prohibitive; whereas by this process it is easily done.

When the said ribs are pressed down the 35 holder lying flat, the rear end of the holder spreads out, but it cannot spread out up at the head because it is tied by the metal in the head. Therefore the major portion of the channel, (now elongated) tapers gradually vertically, being deepest at the rear end, 40 as shown in Figs. 1, 4, and 5, and it makes more room for bent cutters or cutting tools where room is needed.

All holders made by this process carry a 45 distinguishing mark, a natural trade-mark, so to speak, in two slightly depressed bending lines, *i*, or a double bending line on each side, formed by bending the metal when the ribs are pressed down. They run from the 50 rear end parallel with the channel and apparently unite at the head.

This application is a continuation of my 55 application for improvements in turning tool holders, Serial No. 602,987, filed November 24, 1922.

Having thus fully described my invention, I submit the following claims:

1. The method of forming a turning tool 60 holder which comprises forging a body of metal into approximately final external shape and provided with a longitudinal rib or bulge on each side of said body extending throughout a portion of its length, forming a longitudinal bore from end to end of said body and concentric with said ribs, the por-

tion of said bore which is co-extensive with the ribs being of larger diameter than the remaining portion, broaching the remaining portion to fit a rectangular cutter, and finally acting upon the ribs to bring the side walls of the enlarged portion of the bore into the 70 plane of the side walls of the broached portion.

2. The method of forming a turning tool 75 holder which comprises forging a body of metal into approximately final external shape and having a longitudinal rib or bulge on each side thereof, drilling a longitudinal hole from one end of said body toward the other on a line concentric with said ribs to form a cutting tool receiving bore, drilling a reduced continuation of said bore extending out of the other end of the body, and flattening said ribs to make the distance between the side walls of the large bore equal to the 80 diameter of the reduced continuation.

3. The method of forming a turning tool 85 holder which comprises forging a body of metal into approximately final external shape with a longitudinal rib or bulge on each side thereof extending throughout a portion of the length of the body, drilling a relatively large hole from one end of the body toward the other on a line concentric with said ribs to form a cutting tool receiving bore, continuing said bore through to the other end on a reduced diameter, broaching this latter part of the bore to receive a rectangular cutting tool without increasing the 90 diameter of the bore, and finally mashing said ribs down to make the distance between the side walls of the major bore equal to the distance between the side walls of the small bore.

In testimony whereof I affix my signature.
EDWARD F-G. GIBBS.
